LAUNDRY FLATIRON

Edward Sokolik, New Brighton, Minn.

Application October 6, 1950, Serial No. 188,779

1 Claim. (Cl. 38—93)

1

My present application is a continuation in part of my application Serial No. 746,783 filed May 8, 1947, and now abandoned, for Laundry Flat Iron and relates to improvements in pressing irons and deals particularly with irons useful in pressing garments having buttons sewn thereon dispersed or in rows and equally useful in pressing buttonless garments and garments having flounces, plaits, gathers and the like.

Irons have been produced with grooves or flanges thereupon suitable for pressing beneath portions of buttons sewed to the garment. These irons make it possible to press the garment beneath a portion of each and every button close to the thread by which the button or buttons are sewn to the garment, but not astride the thread without angling the iron, or between normally spaced apart row of buttons without sliding the iron forwardly between each two adjacent buttons subsequently backwardly from therebetween.

The object of such iron is to press only closely to the thread by which the button is sewn beneath a portion of each button without raising each button perpendicularly upon its edge, whereby the straining of the thread, the garment, or breaking the button is prevented.

An object of my invention resides in providing an iron having a construction which enables the portion of the garment astride the button as well as beneath a portion of the button to be pressed without angling the iron as the same is being propelled and in the case of a row of spaced apart buttons without inserting the pointed end between each two adjacent buttons. By sliding the flange of the iron beneath a portion of a button and along one side of the thread thereof and subsequently along the other side of the thread, the entire garment area surrounding the button, or in a row of spaced buttons, the area between the buttons, is pressed.

A further object of this invention is to provide a structure whereby the garment may be pressed beneath the button without straining the thread, the garment, or breaking the buttons as the flat iron is propelled along side the buttons.

These and other objects of my invention will be more clearly and fully set forth in the following specification and claim.

In the drawings forming a part of my specification:

Fig. 1 is a side elevation view of a flat iron showing the general construction thereof.

Fig. 2 is an elevation of the butt end showing the ledges formed within the sides of the body.

Fig. 3 is a longitudinal section on line 3—3 65

2

Figure 1, showing the flange dimensionally increased from the front end to the butt.

Fig. 4 is an elevation of the butt of a modified form showing the flanges projected laterally from the body.

The flat iron is indicated in general by the letter A.

The flat iron includes a pressing body which is indicated in general by the numeral 7 and a handle structure indicated by the numeral 8. As the handle structure includes no part of the present invention, it will not be described in detail. The pressing body 7 may be somewhat varied in shape, particularly the rear end-portion, 15 and in the form illustrated includes a pressing bottom 14 merging with the sides 13.

Each of these sides 13 has a convexly bowed front end-portion 15 converging at the pointed end 11 with the other.

It is important that the front end-portions 15 are convexly bowed, and modified by a recess 9, formed preferably in both of the convexly bowed front end-portions 15 of the sides 13 to attain results subsequently disclosed.

The shape of the rear end 12 is illustrated as blunt, but this is not important and the posterior side portions 17 may be of any shape. A shape slightly arcuately converging to each convexly bowed end-portion 15 is illustrated.

A feature, as indicated in Figures 2, 3 and 4 of the drawings, consists in providing, preferably both sides 13 with a groove 18 extending preferably the full length of each side 13 from the pointed end 11 to the rear end 12. This groove 18 is disposed slightly above the pressing base 14 to form the flange 19 coplanar with the pressing base 14 of the pressing body 7. These flanges 19 preferably slightly increase dimensionally, particularly in width, from the pointed end 11 to the rear end 12 and are so pitched and so dimensionally increased as to be adapted for buttons 20 of various sizes normally sewn onto garments 21, to ride upon, when the flange 19 is slid alongside the thread beneath a portion of the button 20, at an acute angle, thereby preventing straining of the thread 23, garment 21, or breaking the button 20.

Another feature of my present invention, as best indicated in Figure 3, resides in the provision of an iron having convexly bowed front end-portions 15 of each side 13 thereof converging to the pointed end 11. Preferably both of these bowed end-portions 15 have a concavely arcuate recess 9 merging with convexly arcuate shoulders 10 formed therein. Each recess 9 including its

3

shoulders 10, comprises nominally the medial substantially one-third of the bowed front end-portion 15 of each respective side 13, so that the shoulders 10 cooperate with the respective concavely arcuate recesses 9, whereby the flange 19 is expeditiously slid along underneath a portion and closely to the thread 23 of each and every button 20 sewn to the garment 21, and whereby the garment 21 is pressed on one side of, and astride the thread 23 by which the said each and every button 20 is sewn, simultaneously, up to a predetermined distance, which normally is at least up to the diametrical line of the said each and every sewn button 20, and in the case of a row of normally spaced apart buttons 20, the portions of garment 21 between the buttons 20 of the row. The convexly bowed front end-portion 15 of each side 13 with a recess 9 formed intermediately therein, presents a conformity, so that the shoulders 10 thereof reach between the buttons 20 in a row of buttons and at the same time the pointed end 11 is caused to approach each button on the same side 13 on which the iron is propelled.

In Figure 3 of the drawings I disclose a series of buttons 20 which are arranged along a center line 24 and are stitched to the garment 21 by fastening thread 23. As will be noted from this figure, when the center button of the series illustrated is engaged in the recess 9 so that the button is resting upon the flange 19, the center line 24 extends over the flange 19 at least up to the diametrical line of the buttons 20. The shoulder portions 10 of the flange 19 astride the recess 9 extend preferably over the center line 24. As a result the garment 21, between the buttons 20 of a row is pressed as the iron is moved closely along the row of buttons.

In view of the fact that the center line 24 extends generally over the flange 19, it is necessary that the iron travel along a wavy path in order to completely press the garment 21. However, the buttons 20 themselves tend to guide the iron in its path and by exerting slight lateral pressure upon the iron 7 as it moves along the row of buttons 20, the iron will automatically travel along the necessary path to completely press the garment 21. At the same time, the recesses 9 do not interfere in any way with the normal use of the iron in pressing garments of any type.

It is recognized that the conventional iron is curved toward the front or pointed end and that accordingly the conventional iron is capable of partially pressing the garment 21 between the buttons, if the buttons 21 are spaced a sufficient distance apart, but it definitely will not press astride individual buttons as it engages them convexly. However, with most garments in which the buttons are fastened normally closely together, it is impossible in most instances adequately to press the area between the closely spaced apart buttons without inserting the pointed end 11 of the iron between each adjacent two buttons. By forming the concavely arcuate recess 9 with convexly arcuate shoulders 10 in a side 13 of the iron at a point substantially distant from the front pointed end 11 of the iron, the shoulder portions 10 of the flange 19 are sufficiently bulged to reach astride each intermediate button in the recess 9 and the adjacent buttons to adequately press this area. As a result considerable time and effort is saved in pressing the garment 21. The flange 19, the recess 9 and the shoulders 10, cooperate to produce an iron of optimum utility.

4

The construction illustrated in Figure 4, is quite similar to that shown in previous drawings. The iron shown in this latter figure is indicated in general by the letter B and differs mainly from the iron A in the shape of the iron body 25 above the flange 19. In place of having an elongated groove 18 along each side of the iron as in the previously described structure, the iron B is provided with a laterally extending flange 26 on each side thereof projecting outwardly beyond the remainder of the iron body. In the case of the modification shown in Fig. 4, both the body portion 25 and the flange 26, although not specifically shown, would have the convexly curved portions 15, disclosed in Fig. 1, and both body 25 and the flange 26 would be laterally depressed into a recess identical with recess 9, previously disclosed, and therefore would in all respects conform with the general disclosure of Fig. 3.

In accordance with the patent statutes, I have described the principles of construction and operation of my pressing iron, and while I have endeavored to set forth the best embodiments thereof, I desire to have it understood that these are only illustrative thereof and that obvious changes may be made within the scope of the following claim without departing from the spirit of my invention.

What I claim is:

30 A laundry flat iron for pressing fabric having a row of buttons secured thereto comprising, a body portion having a lower flat ironing face, said body portion having sides, the forward portions of said sides converging forwardly and providing a forward tapered portion, said sides having a continuous recess which extends from the rear end of one side to the rear end of the other side and around the reduced end of the forwardly tapered portion, said recess forming a flange, the lower face of said flange forming a continuation of said ironing face, the upper face of the flange being disposed adjacent to said ironing face so that the flange is vertically thin, said flange being provided upon each side of the forwardly tapered portion with two convex outer edges and a concave outer edge disposed between the said convex outer edges, said outer edges being arranged in a longitudinal group which longitudinal group is confined within the length of the forwardly tapered portion, the inner wall of the recess upon each side of the body portion conforming to the contour of the outer edges of the flange, the arrangement being such that the buttons will enter the recess and slide upon the vertically thin flange and will be held in a generally horizontal position.

EDWARD SOKOLIK.
